UNITED STATES PATENT OFFICE.

WALTER B. REPERT, OF DUNKIRK, NEW YORK.

CHIROPRACTIC TABLE.

1,376,229.

Specification of Letters Patent. Patented Apr. 26, 1921.

Application filed April 12, 1920. Serial No. 373,194.

To all whom it may concern:

Be it known that I, WALTER B. REPERT, residing at Dunkirk, in the county of Chautauqua and State of New York, have invented new and useful Improvements in Chiropractic Tables, of which the following is a specification.

This invention relates to supporting tables used for medical or surgical purposes, and 10 has for its object the provision of a table designed to support a human body in thoroughly relaxed condition so that the patient will be in proper condition for manual manipulation of the joints, vertebrae, and the like, or any other manipulation forming a 15 part of the chiropractic art as practised by osteopaths and the like.

An important object is the provision of a table of this character which includes an 20 abdominal support which is supported upon a plurality of longitudinally disposed coil springs extending therebeneath, the springs being always under tension.

Another object is the provision of a device 25 of this character which includes front and back supporting benches adapted to support the head and legs of a patient, these benches being longitudinally adjustable toward or away from each other to accommodate patients of different statures, and which further includes an adjustable chest support, the position of which may be varied irrespective of the position of the forward bench or head rest, the abdominal 35 support above referred to being disposed between this chest support and the rear bench and being so mounted that it is absolutely independent of the adjustment of the benches.

40 A further object is the provision of a device of this character in which the rear bench or leg supporting member includes a stationary and a vertically swingably adjustable portion whereby certain positions 45 of the body upon the bench may be obtained.

A still further object is the provision of a device of this character which includes a support adapted to remain permanently 50 upon the floor and which pivotally supports the table proper whereby the table may be swung upwardly into substantially vertical position when desired.

An additional object is the provision of 55 a table of this character which will be highly advantageous as providing the maxi-

mum comfort for the patient, which will facilitate the manipulating operations, which will be highly efficient and durable in use, and a general improvement in the art. 60

With the above and other objects and advantages in view, the invention consists in the details of construction to be hereinafter more fully described and claimed, and illustrated in the accompanying drawings in 65 which—

Figure 1 is a side elevation of the device in normal position,

Fig. 2 is a similar view showing the table proper swung upwardly, 70

Fig. 3 is a plan view with the parts arranged as shown in Fig. 1,

Fig. 4 is a top plan view of the stationary portion of the frame,

Fig. 5 is a bottom plan view of the movable portion, 75

Fig. 6 is an end elevation,

Fig. 7 is a cross sectional view taken through the abdominal support,

Figs. 8, 9 and 10 are detail views showing the adjustability of the front and rear benches and the chest support, and 80

Fig. 11 is a side elevation showing a modified form of the device in which only a stationary frame is employed. 85

Referring more particularly to the drawings, I have shown my table as comprising a stationary base including front and rear end castings 15 and 16 connected and spaced apart by longitudinal bars 17. The front 90 casting 15 has its lower portion enlarged and flattened to provide feet 18 and has its upper portion formed with a shoulder 19 for a purpose to be described. The rear casting 16 has its lower portion flattened to 95 provide feet 20 which are recessed at their upper edges, as shown at 21, for a purpose to be described. The rear casting 16 is formed at its upper portion with spaced upwardly and rearwardly curved arms 22. 100 The feet 18 and 20 are flattened and formed relatively large so that the device will not cause any damage to rugs or floors.

The movable portion of the device comprises a pair of spaced parallel tubes or 105 rods 23 which are connected at their forward ends by a casting 24 which carries a depending arm 25 having a shoulder 26 engageable upon the top of the casting 15 and having pivoted thereon a spring-pressed 110 latch 27 engageable beneath the shoulder 19 for holding the movable portion of the de-

vice down onto the stationary portion or base. At their rear ends the tubes 23 are connected by a casting 28 which is formed with one or more cup-like extensions 29. 5 The recesses 21 in the casting 16 are for the purpose of receiving the rear extremities of the tubes 23 when the movable portion of the device is in upright position, as shown in Fig. 2. At points spaced from their rear 10 ends, the tubes 23 carry castings 30 which are pivotally connected, as shown at 31, with the extremities of the arms 22, this construction permitting the movable portion of the device to be swung in a vertical 15 plane, as will be obvious.

Pivoted between the arms 22 by the pivots 31, are bars 32 which carry cylindrical projections 33 slidably engaged within the extensions 29 and coil springs 34 are located 20 within the extensions 29 and engage against the piston-like projections 33. At their ends the bars 32 are pivotally connected with a step 35 to the free end of which are connected braces 36 which are connected at their 25 other ends with the bars 32 adjacent the arms 22. Pivotedly connected with an angular extension 37 on each side of the casting 28 is a link 38 which has its other end connected with a rod 39 connected with one end 30 of a coil spring 40. The rear casting 16 is provided with inclined recesses 41 within which the angular extensions 37 on the casting 28 may be engaged, as will be herein- 35 after explained.

Slidably disposed upon the tubes 23 is a casting 42 having sleeve portions 43 engaged upon the tubes and held in position by set screws 44. The numeral 45 designates broadly the rear bench of the device which 40 includes a cushion 46 supported upon boards or plates 47 and 48 hingedly connected at 49. The board 47 carries on its underside a bracket 50 which is pivotally connected with the casting 42. Also secured upon the underside of the board 47 adjacent the hinge 49, is a bracket 50 with which is pivotally connected one end of a curved bar 52 which is slidable through the casting 42 and which is pivotally connected at its other end with 45 a bracket 53 secured on the underside of a board 47. The casting 42 carries a set-screw 54 which is engageable with the arm 52 whereby to hold this arm in adjusted positions, for the purpose of securing the bench 45 at different angles to the horizontal. 50

Adjustably mounted upon the tubes 23 near the forward ends thereof, is a casting 55 which includes sleeves 56 slidable upon 60 the tubes 23 and having set-screws 57 engaging the tubes. The numeral 58 designates the head rest which is cushioned and which carries on its underside a bracket 59 pivotally connected with the casting 55 and 65 which also carries on its underside a curved

arm 60 slidable through the casting 55 and engaged by a set-screw 61 by means of which the head rest may be adjusted for disposition at different angles to the horizontal. It will be observed that by adjusting the casting 55 longitudinally along the tubes 23, the position of the head rest with respect to the rear bench 45 may be varied. 70

The numeral 62 designates the chest support which is cushioned and which is supported by a bracket 63 secured to the casting 55. 75

The most important feature of the invention is the abdomen support which comprises a cushion 64 disposed between the rear bench 45 and the chest support 62 and this cushion rests upon a plurality of coil springs 65 which are secured to the free edge of the board 48 at one end and which are secured at their other ends to brackets 80 66 extending upwardly from the casting 24. 85

In the use of the device it will be seen that the movable portion is disposed in horizontal position upon the stationary portion and held in such position by the latch 27. The rear bench 45 and the head rest 58 are adjusted longitudinally upon the bars 23 to be disposed at the desired distance apart to accommodate the patient. The head rest 58 is adjusted to the desired 90 angular position and the board 47 of the rear bench is also adjusted to the proper angular position to insure absolute comfort to the patient so as to produce or permit an absolute relaxation of all the muscles so as to facilitate the manipulation of the vertebrae and lumbars. The springs 65 which support the abdominal cushion 64 are always under tension and the tension may be increased or decreased by shifting 95 the rear bench 55 along the tubes 23. This cushion will support the patient's abdomen in a very comfortable position. It will be observed that the springs 65 are absolutely unaffected by the angular adjustment of 100 the rear bench or by either the longitudinal or angular adjustment of the head rest. It will be observed that owing to the springs 34, the step 35 will be resiliently supported and may yield in proportion to 105 the weight exerted thereon. 110

When the use of the device is not desired, the movable portion may be swung into substantially vertical position, as shown in Fig. 2, with the rear extremities 120 of the tubes 23 disposed within the recesses 21 and with the angular extensions 37 engaging within the inclined recesses 41.

Referring to the modified form shown in Fig. 11, it will be seen that the structure 125 of the essential features is the same, the only difference being in the stationary support. In this form the stationary support comprises spaced tubes 73 similar to the tubes 23 supported by end castings 74 and 130

- 75 having flattened feet 76. The rear bench, head rest, chest support, and abdomen support are exactly the same as in the previously described form but it will be obvious 5 that there is no provision made for swinging the device into substantially upright position. The operation is of course the same as that of the previously described form.
- 10 While I have shown and described the preferred embodiment of my invention, it is of course to be understood that I reserve the right to make such changes in the form, construction, and arrangement of parts as 15 will not depart from the spirit of the invention or the scope of the subjoined claims.
- Having thus described my invention, I claim:
- 20 1. A device of the character described comprising a pair of spaced parallel horizontal supporting rods, supports therefor, a pair of members longitudinally slidably adjustable upon said rods, a head support 25 angularly adjustable upon one of said members, a chest support adjacent said head support, a legs support carried by the other of said members and including a relatively stationary section and a hinged section, means for tilting said hinged section, 30 and a spring supported abdomen engaging member suspended between said head and legs supports.
2. A device of the character described comprising a pair of spaced parallel horizontal supporting rods, supports therefor, a pair of members longitudinally slidably adjustable upon said rods, a head support 35 angularly adjustable upon one of said members, a chest support adjacent said head support, a legs support carried by the other of said members and including a relatively stationary section and a hinged section, means for tilting said hinged section, 40 a spring supported abdomen engaging member suspended between said head and legs supports, a supporting frame upon which said rods and their associated parts are mounted for vertical swinging movement, and catch means for retaining the 45 rods in vertical position.

In testimony whereof I affix my signature.

WALTER B. REPERT.
